UNITED STATES PATENT OFFICE

WALTER H. COLES, OF TROY, OHIO, ASSIGNOR TO THE SKINNER IRRIGATION COMPANY, OF TROY, OHIO, A CORPORATION OF OHIO

LAWN SPRINKLER

Application filed December 31, 1924. Serial No. 759,185.

My invention relates generally to the type of lawn sprinklers wherein revolving lateral spraying nozzles are caused to rotate by the force of the water against the air into which it is ejected and wherein the movement of the spraying nozzles is in a direction contrary to that in which the spray of water is ejected. Particularly my invention relates to a novel sprinkler in which separate self-actuated spraying means are so connected by intermediate mechanism that a direct and positive inter-relation is established.

My invention has as its object improvement in the practical uses of such spraying devices so that the speed of revolution of the primary spraying means may be held within limits which will afford the greatest effectiveness of the distribution of water from the nozzles.

In the existing type of sprinkling device in which the rotation of smaller lateral nozzles motivates and determines the rate of a larger revolving nozzle delivering the bulk of water sprayed therefrom, not only does the speed of rotation depend upon the water pressure but the motive power for rotation has been derived from the smaller rotating arm, as the larger nozzles have been placed in a central axial position. In the present construction the novelty as compared to the type of sprinkler described lies in placing the large nozzles on the ends of two freely revolving arms removed from the central axial position, utilizing as motive power either one or more large nozzles and by means of moving this nozzle to the end of a radial arm, deriving the power from the ejection of water from this large nozzle to serve as an adequate motive power for the rotation of the sprinkler. In my invention two large nozzles are used mounted on the ends of two arms. This is in addition to two small rotating nozzles and the rotating power is derived from four nozzles instead of merely the two smaller ones.

In this construction by connecting through a chain of gears the two pairs of rotating arms and utilizing the ejection force of the water on all four of the nozzles, a maximum amount of motive power is obtained.

In sprinklers previously constructed which

use two nozzles as main distributing sources which are mounted on the ends of radial arms, the speed of rotation from these main nozzles is, under ordinary operating pressures, so high that the distance of the throw of the stream is materially reduced because of the rapid motion of the ejecting nozzle around a center.

The novelty in my construction lies also, as compared with the type of sprinkler just described, in utilizing as motive power the ejective power in the large main distributing nozzle and in a speed controlled by means of a governing device, so that these large main rotating nozzles travel at a slow speed and give the full throw and distributing quality of the nozzle, avoiding the reduction in distance which would be caused by a more rapid revolution.

Contrasting my invention with a sprinkler using a central large nozzle motivated by small rotating sprinkling arms, this device adds the motive power developed by the large spraying nozzle making the sprinkler much more effective.

Contrasting my construction with sprinklers on which two main nozzles are mounted on radial arms, this sprinkler provides a governor which reduces the rotating speed to a point where the most effective watering qualities are obtained.

My invention provides a maximum of motive power, utilizing the ejection force of all the water distributed and it also provides a governing device which maintains the speed of rotation within effective limits. The free action of the large arms and the utility of the small arms as a governor, the small arms serving as motive power for the large arms only when some abnormal condition prevents their free rotation, is a distinctive feature of my invention. In the particular construction described the governing mechanism selected is the pair of small distributing arms geared—at a higher speed of rotation—to the arms which carry the large distributing nozzles. The use of the small rotating arm as a governor has, however, some advantages as a governing mechanism which would not exist in a mere escapement.

The principle of operation of this governor is that the small rotating arms under a given pressure, operate normally at a fixed speed. Up to this speed the tendency of the rotating arm is to overcome any resistance which would retard the speed. Beyond this point the tendency is to resist any power which would tend to increase the speed beyond its normal operative rate. By gearing together the two sets of arms in suitable ratio, each of which has a normal operating speed, the gear mechanism can be so arranged that an equilibrium will be established whereby the small arms will exceed their normal speed and the arm carrying the large nozzles will be considerably reduced in speed until it reaches the effective operating speed. An equilibrium is thereby established. By increasing the ratio in the gear train, the small arms can be made to serve solely as a governing device, and the speed of the small arms will not be affected by the motive power of the large arms.

The tendency of operation, therefore, is as follows:—With both sets of nozzles spraying and with the properly calculated gear connection, the large nozzles will rotate very slowly and the smaller arms acting as a governor will operate more rapidly than normally, an equilibrium being thereby established with slow moving large nozzles and rapidly moving small nozzles, and an equilibrium utilizing the full flow of the water from all nozzles as motive power.

With any tendency toward stoppage on either pairs of nozzles, the tendency toward slowing down is compensated for by the power of the other nozzles.

If any increased pressure tends to increase the speed of the large nozzle, this tendency is counteracted by the excessive amount of power required to revolve the small nozzles at a considerably increased rate, and the smaller rotating arms act as an effective governor controlling the speed within satisfactory limits, so far as the large nozzles are concerned.

The use of the rotating sprinkling arm accomplishes the same purpose as the governor. It also adds the benefit of a slight additional motive power in emergencies. It affords additional sprinkling facilities. It actuates a chain of gears from each end of the chain.

In the drawing:

Figure 1 represents a top perspective view of my device.

Figure 2 is a vertical cross section along the lines 2—2 of Figure 1.

Referring to the drawings in detail, the base 1 has a suitable water passage 2 cast into its structure which is provided with a swivel hose connection 3 and extends upward from the base in a threaded nipple 4. A sleeve 5 is attached to the exteriorly threaded nipple 4 by means of interior threads 6. The sleeve

5 has on its upper end an inwardly extending shoulder 7 which retains the shoulder 8 of the bushing 9 disposed within it. This bushing 9 extends upwardly through the outer sleeve and has threads 10 at its top onto which a hollow casting 11 is screwed. The hollow casting 11 has threaded openings 12 laterally disposed therein which admit the pipes 13. On the ends of these pipes the spraying nozzles 14 are attached which are preferably of needle valve type with opening 15 in which the discharging aperture is controlled by a needle actuated by the exterior controlling valve handle 16. These spraying nozzles are pointed in such direction that the ejection of water therefrom will impart a counter motion to the pipes to which they are attached and a consequent rotation of the casting 11 around the axial support, the upper portion 17 of the bushing 9 rotating within the shoulder of the outer sleeve 5, and within the collar 18 of the large fixed gear wheel 19, which has radial spokes 20 which are attached to the non-rotating sleeve 5 by screws 21. On the hollow casting axially aligned with the lower rotating bushing 9 a collar 21^a threaded into the casting forms an upward thrust bearing for the flange 22 of the top spraying arm carrying piece 23, into which are threaded on opposite sides pipes 24 which are preferably bent on a horizontal plane inwardly at their exterior ends in a direction opposite to that in which the ejection force of the water in the nozzles 25 attached to their ends causes their rotation. The construction of the two sets of spraying nozzles is therefore such that if it were not for the gearing controlling their movement, each would rotate independently of the other.

The gearing which causes each set of nozzles to act as a driving impetus to the other up to a certain speed of rotation and then as a brake is disposed as follows: A pinion 26 is attached to a shaft 27 which has its bearing vertically through the casting 11 and it meshes with the large fixed gear wheel 19 below the casting 11. On the upper end of the shaft 27 above the casting 11, a gear wheel 28 is disposed which meshes with a pinion 29 which also has vertical bearing on the casting 11, being attached to the shaft 30. To the upper end of the shaft 30 a gear wheel 31 is attached which meshes with a pinion 32 which is disposed in fixed position as a collar about the sleeve-like lower portion of the top spray arm carrying piece 23. In this manner I practically demonstrate a suitable mechanism for controlling a rotating arm, on which major spray nozzles are attached, by means of a governing device, which in this instance is a secondary rotating sprinkling arm operated at a higher speed through a chain of gears.

I also practically demonstrate the use for such a controlling device of secondary

5 spray nozzles connected by intermediate gearing device to the arms carrying the major spray nozzles, in such a manner that each acts as an impulse or as a brake for the other, as previously described, thereby securing a maximum rotating movement, at a given volume emission and an automatic self-governing control.

10 I do not wish to be limited to the particular size construction or gearing disposition particularly described herewith as many changes of size and disposition of parts will readily occur to those skilled in this manufacture.

15 Having thus described my invention and further described a particular construction by which I accomplish my object, what I claim and desire to secure by Letters Patent, is:—

20 1. In a lawn sprinkler, a water passage member, a supporting member rigidly supported thereby, a sleeve axially aligned with axis of said supporting member and rotatable within same, a rotatable supporting member attached to the upper end of said sleeve, arms with sprinkler heads attached to said rotatable supporting member, a sleeve mounted in said rotatable supporting member, an upper supporting member attached to upper 25 end of said sleeve, arms with spraying nozzles attached to said upper member and means for causing a counterbalancing motive reaction from the ejection force of the water from the sprinklers between said upper 30 and lower rotating arms.

35 2. In a lawn sprinkler, two sets of rotatable spray arms mounted independently, one of said sets having large volume nozzles, and the other having secondary nozzles, each 40 of said sets motivated by the ejection of water from its respective nozzles, and intermediate mechanism providing a governing means whereby each set shall act to govern the other in ratio dependent on the operating 45 speed thereof.

50 3. In a lawn sprinkler, sets of rotatable arms having nozzles disposed in radially balanced position with reference to a central hub, each set of arms being constructed 55 to be rotated by the ejection of water from its respective nozzles and governing means for said sets of nozzles to cause said several sets to rotate at different speeds, comprising intermediate mechanism which affects the operating speed of each set of arms in accordance with the operating speed of the other.

60 4. In a lawn sprinkler, sets of spraying arms having aligned axes, one of said sets having volume controlling means adjustable for controlling the volume of water sprayed therefrom, and another set of spraying arms having secondary spraying means, with controlling means intermediate said sets of arms 65 adapted to control the operating speed of

said first set of arms in a ratio directly proportionate to the speed of said other set.

5 In a lawn sprinkler, a set of sprayers disposed on radiating arms, said set motivated by the ejection of said sprayers, a second set of sprayers on a second set of radiating arms, said second set of sprayers providing the motivating power for said second set of arms, each of said sets mounted on separately revolving hubs, a train of 70 gears mounted in fixed relation to said second set of arms, said train of gears being connected with said first mentioned arms, and said gear train having teeth thereon arranged in such ratio that during intervals 75 of connected relation the fixed gear will act as a governor controlling the normal free operating speed of said first arms by the second.

6 In a lawn sprinkler, a set of sprayers disposed on radiating arms, said set being 80 constructed to be rotated by the ejection of water from said sprayers, another set of sprayers on other radiating arms also constructed to be rotated by the ejection of water from said other set of sprayers, said 85 sets independently mounted in axial alignment, and governing means for said sets of sprayers to cause said several sets to rotate at different speeds, comprising means fixedly connected with said second set of arms adapted to be interconnected with said first set of arms, said means providing a speed controlling device operable directly proportionate to the operating speed of said second set of arms for controlling the speed of said 90 first set.

7 In a sprinkler in combination with a support and means for supplying water thereto, a variable speed controlling assembly 105 comprising nozzles independently and rotatably mounted on said support, said nozzles being each constructed to be rotated by the ejection of water therefrom, said nozzles having water outlets of different areas, and means mechanically connecting 110 said rotatable nozzles comprising a reduction train of gears from the smaller nozzle to the larger nozzle.

8 In a lawn sprinkler, a water passage member, a supporting member rigidly supported thereby, a rotating member, means for supporting in said supporting member an axial support for said rotating member, an upper rotating member, means for supporting in said lower rotating member an axial support for said upper rotating member, each of said rotating members being constructed to be rotated by the repulsive force of the water ejected therefrom and means for controlling the rotation of each rotating member by the other up to a certain speed, and said means adapted to act as a brake at speeds greater than said certain speed.

9. A sprinkler of the character described 130

comprising a plurality of spray nozzles each rotated during operation of the sprinkler by the ejection of water therefrom, and governing means for said spray nozzles to cause said several nozzles to rotate at different speeds, comprising means interconnecting the said nozzles to control the speed of rotation thereof one with respect to the other.

10. A sprinkler of the character described comprising a plurality of spray nozzles mounted for separate rotation, each adapted to be rotated during operation of the sprinkler by the repulsive force of the water ejected therefrom, and means interconnecting the 15 said nozzles comprising gears arranged to reduce the natural rate of rotation of one nozzle by controlling said rate of rotation through said gears by the rate of rotation of said other nozzle.

20. 11. A sprinkler of the character described comprising a plurality of spray nozzles, each constructed and mounted to rotate freely during operation under the repulsive driving force of the ejected water except for a 25 controlling effect exerted by the other nozzle, and governing means for said nozzles to cause said several nozzles to rotate at different speeds, comprising means interconnecting said nozzles constructed to conjointly 30 utilize the driving forces exerted at the several said nozzles.

12. A sprinkler of the character described comprising a plurality of spray nozzles, each constructed and mounted to rotate freely 35 during operation under the repulsive driving force of the ejected water except for a controlling effect exerted by the other nozzle, and governing means for said nozzles to cause said several nozzles to rotate at different 40 speeds, comprising means interconnecting said nozzles so that the speed of rotation thereof is controlled one with respect to the other.

13. In a lawn sprinkler two sets of rotatable spray arms mounted for separate rotation, one of said sets having large volumed nozzles, and the other having secondary nozzles, each of said sets being mounted for rotation by the ejection of water from its 50 respective nozzles and an intermediate mechanism providing a governing control whereby the speed of rotation imparted to each of said sets of nozzles by the repulsive force of the water ejected therefrom is controlled in accordance with the speed of rotation imparted to the other set of nozzles by the repulsive effect of the water ejected from the other set of nozzles.
